PROCESS FOR CONVERTING THE WEBS FROM THE CARDING
ENGINES INTO FINE ROVINGS FOR SPINNING
Original Filed Feb. 21, 1930

Inventor:
Guillame C. Laurency
Richards & Geier Attorneys

UNITED STATES PATENT OFFICE

GUILLAUME CLEMENT LAURENCY, OF LA HULPE, BELGIUM

PROCESS FOR CONVERTING THE WEBS FROM THE CARDING ENGINES INTO FINE ROVINGS FOR SPINNING

Original application filed February 21, 1930, Serial No. 430,386, and in Belgium February 5, 1930.
 Divided and this application filed November 28, 1930. Serial No. 498,533.

This application forms a division of my application Ser. No. 430,386, filed Feb. 21, 1930, hereinafter referred to as my said copending application.

5 My invention can be applied to any actually known type of carding engines for textile fibres, and it has for its object to produce by means of said carding engines fine regular rovings which can be transformed into thread in the spinning machine by drawing the filaments without twisting them. However I contemplate more particularly to use my invention with carding engines which produce a web of perfectly straight and parallel fibres such as described in my said copending application, and therefore my invention has also 10 for its object to transform in the spinning machine fibres straight from the carding engines.

20 My invention is described with the aid of the appended drawing in which:

Fig. 1 is a longitudinal view partly in section of the mechanism for grouping the fibres into parallel rovings, said mechanism being mounted in combination with the mechanism for stretching the fibres into parallel relation according to my said copending application.

Fig. 2 shows some details of Fig. 1 by an elevational view at 90° to the latter,

Fig. 3 is a front view of the teeth of the rakes on an enlarged scale, and

Fig. 4 is a lateral view of the same.

In Fig. 1 showing a complete grouping mechanism, A is a part of the comber or doffer of the card, B a section of the roller taking the fibres from the doffer A. D is a roller provided with needles or carding teeth, the circumferential speed of which is greater than that of the roller B. This increase of speed causes the needles or carding teeth on D to slide between the fibres held at the point n by the roller B. After they are no longer held at said point n, said fibres will remain between the teeth on D and conveyed by the latter to the point o, where they will be taken at a still greater speed by the roller E similar to the roller B, the sliding movement of the fibres between D and E being effected in the same way as between A and B.

50 While being stretched between D and E

the fibres will be grouped in rovings by the action of a rake M partly shown at a larger scale in Figs. 3 and 4. The teeth of said rake go up and down very quickly between the fibres. At each upward movement the points thereof will be inserted between the fibres, thus exactly marking the point of separation thereof, and as said teeth continue their upward movement the tapered shape thereof will widen the opening by forcing the fibres laterally to the right and left, so that all the fibres taken between two points of the teeth will be assembled in groups, said groups being progressively spaced from each other as they will become narrower. The groups of fibres conveyed by the roller E to the point u will be taken by the roller F with very little acceleration of speed and transmitted to the condensing point v where they will be rolled in the known way by the friction of the muffs G and G'.

A second rake N operates between the rollers E—F for the purpose of producing the separation of the groups of fibres; the amplitude of vertical movement of said rake N may be reduced, said rake may even be held stationary for short fibres, but for long textile fibres vertical or lateral movement of the rake is indispensable.

The points of the teeth on the rake M should be lowered below the fibres after each downward movement, whilst the teeth on the rake N may remain between the groups of fibres. The teeth on the rake M have ribs with hooks p (Figs. 3 and 4); upon the lowering of the teeth said hooks p will cause the stray fibres to rejoin the groups to which they belong. Said rib is not necessary on the rake N.

In practice and more particularly each time after the cleaning of the cards it is necessary to momentarily prevent the action of one or both rakes M, N. The mechanism has been combined to this end. The rakes are secured at their ends to vertical rods L slideable in guides b and raised by the action of springs d (Fig. 2).

The crank pulley R causes the rocking of the balance beams e on the shaft f through the agency of connecting rods S and arms q, 100

said rocking movements being transmitted to the vertical rods L by links g pivotally connected to pieces h moved upwardly and downwardly at each revolution of the pulley R.

5. The pieces h are adapted to freely slide on the rods L above the rings h' secured to said rods and held against the pieces h by the action of springs d if the rakes are to be operated.

Furthermore each of the rods L has a nose 10 r located near a pin t secured to a cross bar U, the movement of which causes the corresponding rake to be stopped or operated.

In the position shown in Figs. 1 and 2, the pins t are spaced from the noses r, but if the 15 bar U is pushed towards the right (Fig. 2) the pin will be moved above the nose r and prevent the rings h' from being moved upwardly, whereby the rake will be held at the end of its downward stroke in spite of the 20 action of the springs d. Upon the movement of the bar U to its initial position, said rake may again be operated freely.

In the rovings produced by this process the fibres remain parallel as they were in the 25 web of the carding engine, and as these rovings are produced by strips in the web, which strips have a very precise width, exactly 30 equal to the distance between the points of the rakes, they have a very regular cross-section which enables them to be spun in 35 yarns without being twisted. This is an advantage in comparison to the other processes which involve a complicated machinery to which the rovings are submitted before spinning.

Having now fully described my said invention, what I claim and desire to secure by Letters Patent, is:

1. In machines for preparing textile fibres 40 for spinning, the combination of parallel rollers revolving with successively increased speeds and stretching between them a web of parallelized fibres, and a rake provided with sharp pointed teeth alternately moved in and 45 out of said web several times during the passage of a fibre, whereby the web is divided and grouped into rovings of parallel fibres and of regular section.

2. In machines for preparing textile fibres 50 for spinning, the combination of parallel rollers revolving with successively increased speeds and stretching between them a web of parallelized fibres, and a rake provided with sharp pointed teeth alternately moved in and 55 out of said web several times during the passage of a fibre, said teeth having saw-like ribs, whereby the web is divided and grouped into distinct rovings of parallel fibres and of regular section.

60 3. In machines for preparing textile fibres for spinning, the combination of a plurality of parallel rollers revolving with successively increased speeds and stretching between them a web of parallelized fibres, a rake provided 65 with sharp pointed teeth alternately moved

in and out of the web stretched between the first and second roller, said teeth having saw-like ribs, and a second rake the teeth of which are permanently engaged between the rovings formed by the teeth of the first rake and 70 stretched between the second and the third roller.

4. In machines for preparing textile fibres for spinning, the combination of a plurality 75 of parallel rollers revolving with successively increased speeds and stretching between them a web of parallelized fibres, a rake provided with sharp pointed teeth alternately moved in and out of the web stretched between the first and the second roller, said teeth having 80 saw-like ribs, a second rake the teeth of which are inserted permanently and moved between the rovings stretched between the second and the third roller and formed by the teeth of the first rake, and a common crank imparting 85 motion to both rakes.

5. In machines for preparing textile fibres for spinning, the combination of a plurality 90 of parallel rollers revolving with successively increased speeds and stretching between them a web of parallelized fibres, a slidably mounted rake provided with sharp pointed teeth 95 adapted to be moved in and out of the web stretched between the first and the second roller, said teeth having saw-like longitudinal ribs, a second slidably mounted rake the teeth of which are adapted to be moved between the rovings stretched between the second and the third roller, a single balance beam, a crank imparting balancing motion to 100 said balance beam, non rigid connections between said balance beam and said slidably mounted rakes, whereby said rakes are moved away from the web and rovings, spring means urging said rakes towards said web and rovings, and a separate cam means for operating each rake against said spring means whereby the teeth may be maintained out of said web and rovings.
